L. MILLER & A. E. ELLINWOOD.
GRAIN BINDING HARVESTER.

No. 364,275.

Patented June 7, 1887.

UNITED STATES PATENT OFFICE.

LEWIS MILLER AND AUGUSTUS E. ELLINWOOD, OF AKRON, OHIO; SAID ELLINWOOD ASSIGNOR TO SAID MILLER.

GRAIN-BINDING HARVESTER.

SPECIFICATION forming part of Letters Patent No. 364,275, dated June 7, 1887.

Application filed June 2, 1884. Serial No. 133,498. (No model.)

To all whom it may concern:

Be it known that we, LEWIS MILLER and AUGUSTUS E. ELLINWOOD, both of Akron, county of Summit, and State of Ohio, have invented a new and useful Improvement in 5 Grain-Binding Harvesters, of which the following is a full, clear, and exact description, reference being had to the accompanying drawings, making part of this specification.

10 Our invention relates to the means for tripping and releasing or stopping and starting the binding mechanism, and for regulating the size of the bundles, and to means for locking or holding the binding mechanism gearing 15 against back action or throw during the time it is thrown out of action, and will be understood from the following description, reference being had to the accompanying drawings, in which—

20 Figure 1 is a front elevation of so much of a harvesting-machine as is necessary to show our improvements. Fig. 2 is a plan view of a portion of the same. Fig. 3 is a front elevation of the tripping mechanism detached, showing also 25 other parts in connection with which said tripping devices act. Fig. 4 comprises two detail views of the clutch connected with the main binder-gear shaft, and Fig. 5 represents a horizontal section through the binder-gear stand- 30 ard and a portion of the gear-wheel on the knotter-actuating shaft.

The machine represented in the drawings is 35 of that class in which the grain is bound on an inclined elevating-table located at the inner side of the platform-carrier and receiving the grain directly therefrom, and the devices hereinafter described are arranged with especial reference thereto; but it will be apparent that some of these devices may be used 40 upon other forms of machine, if desired; also, that the machine, in its organization or construction and arrangement of parts as a whole, is similar to others now in use, and need not therefore be described in detail further than 45 is necessary to an understanding of our improvements.

A represents the forward sill of the platform-frame; B, a combined gear-block and chair rigidly secured to the inner end of sill 50 A adjacent to the main drive-wheel, and B' a second chair of less height than chair B, the

chairs B and B' forming supports for the forward ends of two longitudinal binder-frame sills, C and C', which are connected by suitable inclined transverse sills or bars C², forming a support for the inclined binder-table. 55 (Not shown.)

To the forward inclined transverse bar, C², or to the chair B, is secured the binder-gear standard D, having tubular arms D' D², which 60 project rearwardly, one over and the other under the binder-table, and form supports for the needle and knotter-actuating shafts and binder mechanism in a manner well understood. 65

E is a longitudinal bar, supported above the path of the grain to the binding devices by straps and braces e e', connecting it with the upper tubular arm, D², of the binder-gear standard, said bar E forming a support for 70 one end of the knotter-shield E', also for the upper bearing-bracket, E², of the butter-shaft, and in practice for the pendent bearing-brackets of the shaft actuating the pickers or gatherers, as shown in Letters Patent No. 276,448, 75 granted to me April 24, 1883.

F represents the main binder-gear shaft, which is mounted in suitable bearings in the gear-block B and binder-frame, and to which motion is imparted from the main drive-wheel 80 of the machine in any usual or preferred manner.

Motion is imparted from the shaft F to the various operative mechanisms of the machine, and among these to the binding mechanism, 85 as follows:

a represents a pinion loose on the shaft F near its forward end, and adapted to be engaged therewith by means of a dog, a', pivoted to the forward face of the pinion, and adapted, 90 when not rocked inward toward shaft F, by means hereinafter described, to engage a spur, b', on a cross-head, b, rigidly secured to the shaft F, directly in front of the pinion a, for causing the latter to be rotated with the shaft 95 F in a manner well known. When coupled to and rotating with the shaft F, the pinion a serves, through intermediate pinions, a² and a³, to drive a spur-gear, a⁴, fast on the knotter-actuating shaft, c, and thence through suitable 100 crank-wrist, crank, and connecting-rod c² to the vibrating needle-shaft c'.

To the forward inclined transverse bar, C², of the binder-frame, or to other suitable support, is secured a curved or angular bracket, d, having an eye or perforation in its forward end, 5 forming a bearing for a sliding stop or dog, g, projecting downward from the angle or elbow of a bell-crank-shaped arm or bar, G, the upright arm or leg of which is pivoted to a crank, h, on the forward end of a rock-shaft, H, mounted 10 in suitable bearing-brackets attached to the bar E. The arm g' of the angular bar G projects outwardly, and at its outer end rests upon a cam, c⁴, on the shaft c' immediately in rear of the crank-arm c³ on the forward end 15 of said shaft, for a purpose which will be explained.

The rear end of shaft H has a crank-arm, h', formed upon it, which projects outwardly over the knoter-shield E', and has the upper end 20 of a pendent link, i, adjustably connected with it, said link passing down through a slot in the shield E', and having its lower end pivoted to a rod, I, which is pivoted at one end to the knoter-shield E' near the bar E, and at its 25 outer or free end overhangs the grain accumulating on the binder-table to form a bundle.

The rod I lies inclining downward and outward over the binder-table, and as the grain accumulates and becomes packed by any usual 30 or preferred means for that purpose it gradually crowds the rod or arm I upward, and the latter, acting through the link i and arm h', rocks the shaft H, lifting the angular bar G and withdrawing the pendent spur or 35 dog g out of the path of the end or nose a" of the dog a', freeing the latter and allowing it to be forced outward by its spring a^x to engage the cross-head b, and thus coupling the pinion to its shaft for actuating the binding 40 mechanism. As the arm c³ of the needle-shaft is rocked upward, the cam c⁴ on said shaft acts on the arm g' of the bell-crank-shaped arm G, and serves to hold the latter, with the spur g, up out of the path of the end or nose a" on the dog a', forcing said dog inward out of engagement 45 50 with the cross-head b, allowing the pinion a and binding mechanism to remain at rest until the action of the grain on the arm I above described is repeated for again setting the binding mechanism in motion. The height of the 55 free end of arm I may be adjusted as desired by means of a series of perforations in the upper end of its supporting-link i, through any one of which perforations it may be connected by a pin or other suitable fastening with the 60 arm h' of the rock-shaft H. The shaft H is provided with an upright arm, h², having a series of perforations at different distances from the shaft H, through any one of which a spiral spring, j, may be connected with said 65 arm, said spring extending outward and having its outer end connected with a bar, J, pass-

ing outward through a guiding-loop, j', secured to the upper face of the gear-standard sleeve D². The bar J has a notched or ratcheted lower face, adapting it to engage at any point 70 in its length with a tooth formed in the lower wall or side of the loop j', and is provided at its outer end with a loop or handle, j², within convenient reach of the driver in his seat, who, by adjusting said rod J, and with it the tension of the spring j, can regulate at will the resistance to the upward movement of the arm I, and thereby the size of the bundle and the degree of compression of the grain required 75 to lift the arm I for tripping or setting in motion the binding mechanism. 80

For holding the gearing of the binding mechanism and preventing any back action after the binding mechanism has been released from the actuating-shaft F, the gear-wheel a⁴ 85 on the knoter-actuating shaft is provided on its rear face with a cam-shaped projection, k, inclined on its forward face relatively to the direction of movement of the wheel, and having an abrupt rear face adapting it to act upon 90 and crowd backward a roller, l, journaled in the forward end of a sliding pin, L, moving in suitable ways or perforations in the gear-standard D. A spiral spring, l', surrounding the shank of the pin L between a shoulder formed 95 thereon and the rear bearing for said pin, serves to crowd the pin forward, with the roller resting and rolling in contact with the cam k until the latter has passed the roller, when the latter is immediately thrust forward 100 behind said cam just as the wheel a⁴ completes its revolution and is thrown out of action, and thereby serves to effectually hold the latter and the binder-mechanism gearing against any 105 back action.

Having now described our invention, we claim as new—

1. In a grain-binder, a rock-shaft mounted upon the binder-frame and a toothed or notched bar connected adjustably by a spring 110 to a crank-arm on the rock-shaft and engaging a spur on said frame, in combination with a tilting arm in contact with the accumulated grain and connected to the rock-shaft, whereby the resistance of the tilting arm may be varied 115 by the adjustment of the toothed bar, substantially as described.

2. In a grain-binder, a rock-shaft mounted upon the binder-frame and a pivoted lever also mounted upon said frame in contact with the accumulated mass of grain, in combination with a bell-crank-shaped arm connected to an arm of the rock-shaft, a pendent link connecting the pivoted lever with the rock-shaft, and a dog mounted upon the main 125 binder-gear shaft and engaged by the lower end of the bell-crank-shaped arm, substantially as and for the purpose described.

3. A rock-shaft and a pivoted lever mounted upon the binder-frame, said lever being in contact with the accumulated grain, a gear-wheel mounted upon the main binder-gear shaft and 130

carrying a swinging dog, and a cam upon the
needle-shaft, in combination with a bell-crank-
shaped arm connected to a crank-arm upon
said rock-shaft, and having an arm extending
5 in operative engagement with the dog on the
main binder-gear shaft and engaging the said
swinging dog at its lower end, substantially as
specified.

4. The combination, with the gear-wheel
10 mounted upon the main binder-gear shaft and
carrying the swinging dog, and the cross-head
upon said shaft, of the bell-crank-shaped arm
connected to a crank-arm upon a rock-shaft
mounted upon the binder-frame and engaging
15 the dog at its lower end, and the toothed or
serrated bar connected to a crank-arm of the
said rock-shaft and engaging with the upper
arm of the binder-frame, substantially as and
for the purpose set forth.

20 5. The sliding dog for stopping and start-
ing the binder mechanism, in combination
with a cam on the binder-arm shaft for holding
said dog up after it has been raised to trip the
binder mechanism and until the operative
25 movement of said mechanism is completed,
substantially as described.

6. The angular bar provided with the slid-
ing dog for stopping and starting the binder
mechanism, in combination with the rock-
30 shaft and pendent arm or lever adapted to be
acted upon by the grain, and the cam on the

needle shaft for holding up said dog, substan-
tially as described.

7. The pivoted arm or lever I, overhanging
the binder-table and having a link-connection
35 with the rock-shaft, in combination with the
sliding dog having a pivotal connection with
said rock-shaft for tripping the pinion actu-
ating the binder mechanism, substantially as
described.

8. The pivoted arm or lever I, in combina-
tion with its supporting-link, adjustably con-
nected with a crank-arm on the rock-shaft, a
40 sliding dog connected therewith for tripping
the binder mechanism, and a cam on the rock-
shaft for raising and upholding said dog, sub-
stantially as described.

9. The rock-shaft and means, substantially
as described, connected therewith for tripping
the binder mechanism, in combination with 50
the crank-arm and spring, and the ratchet-
bar for adjusting the tension of said spring
and regulating the resistance to the tripping
of the binder mechanism and the size of the
bundles, substantially as described.

In testimony whereof we have hereunto set
our hands this 12th day of May, A. D. 1884.
